UNITED STATES PATENT OFFICE.

GEORGE F. SMITH, OF BALTIMORE, MARYLAND.

CHIMNEY-CAP.

SPECIFICATION forming part of Letters Patent No. 760,265, dated May 17, 1904.

Application filed February 5, 1904. Serial No. 192,072. (No model.)

To all whom it may concern:

Be it known that I, GEORGE F. SMITH, a citizen of the United States, residing at Baltimore, State of Maryland, have invented certain new and useful Improvements in Chimney-Caps, of which the following is a specification.

This invention consists of an improved concrete chimney-cap or other article composed of two completely-formed and hardened concrete parts which are united by connecting the exposed ends of wires embedded in said parts.

In many concrete articles, such as arched chimney-caps, the liability of breakage in handling the same is so great that their use is practically prohibitive. I have therefore devised a novel construction whereby the concrete cap or other article may be made in sections or parts complete, not likely to break in handling, and with one or more wires embedded and with ends exposed, which parts may be assembled at the place where the article is to be set up, at which time the parts may be united by splicing or tying the wire ends together. I also provide an improved base for the chimney-cap.

The invention is illustrated in the accompanying drawings, in which—

Figure 1 is an elevation of a chimney surmounted by one of the improved concrete caps. Fig. 2 is a sectional view of the improved cap and a base on which the cap sets. Fig. 3 is a top view of the two parts of the base and the cap, showing the wires spliced together. Fig. 4 is a broadside view of one part of the cap, showing the exposed ends of the wires. Fig. 5 is a perspective view of the improved chimney-cap base, one corner being in section.

The finished chimney-cap is of the arched form, as seen in Figs. 1 and 2, made of concrete material, and is composed of two equal separate sections or parts A A', each being one-half of the cap, as seen in Fig. 4. Each section is curved and has one or more wires b embedded in it, and the ends b' of the wires project from the edge c that is to abut against the corresponding edge of the other section. Each of these sections may be said

to be an article in itself, because any number of them in this condition are salable as articles or commodities. When two of said sections are set upright on their base edges d and the wired edges c abut, the arch becomes 55 complete, and the wire ends b', projecting at the abutting edges, may then be spliced or united in any suitable way. To make the arched cap more complete, provision is made for concealing the united wire ends. This 60 consists of forming a rabbet-groove e along the edge c that is to abut and arranging the wire ends b' to project from said groove. By reference to Figs. 2 and 3 it will be seen this results in the formation of a channel or furrow 65 extending across the apex of the arch. The wire ends may then be united by twisting two adjoining ends together, as shown in Fig. 2, and then bending said united ends over sidewise into the channel, as shown in Fig. 3. 70 The apex channel may then be filled with plastic concrete e' to cover the said wire ends and to form a suitable finish at the top of the arch. When the plastic concrete becomes hard in the channel, the arched chimney-cap 75 will be complete.

A base to support the concrete arch comprises a concrete slab F, whose exterior edge will have any shape, such as rectangular in the present instance, to suit the chimney on 80 top of which it is to be placed, as in Fig. 1. This slab has an opening g, up through which the smoke from the chimney-flue will issue, and on two sides of said opening on the top of the slab is a groove or depression h, into 85 which the base edges d of the chimney-cap set, as seen in Fig. 2.

In order to strengthen concrete slabs for chimney-tops and prevent them from breaking at the corners, an angle-iron i of L shape 90 is embedded in each corner, as shown in Fig. 5 at the corner that is sectioned. This construction of concrete slab makes a durable finish for the protection of tops of chimneys.

Having thus fully described my invention, 95 what I claim as new, and desire to secure by Letters Patent, is—

1. A section of an arched chimney-cap made of concrete and in the form of a curved slab, and provided with one or more embedded wires 100

and the end or ends of said wires projecting and exposed at one edge.

2. A section of an arched chimney-cap made of concrete and in the form of a curved slab, 5 and having a groove along one edge and provided with one or more embedded wires and the end or ends of said wires projecting at said groove and exposed, as set forth.

3. A concrete arched chimney-cap having 10 two curved sections each separately formed and each provided with embedded wires which extend upward to the apex of the arch where the ends of the wires are exposed and said wire ends of one section being twisted or 15 otherwise united to the wire ends of the other section.

4. A concrete arched chimney-cap having base edges, and a concrete base-slab to rest upon the top of a chimney and provided with 20 a smoke-opening and said slab having on top and at two sides of said opening a groove or depression into which said base edges set.

5. A concrete arched chimney-cap having base edges, and a concrete base-slab to rest 25

upon the top of a chimney and provided with 25 a smoke-opening and with seats for said base edges and having angle-irons embedded at the corners.

6. An arched chimney-cap comprising two separate sections each forming part of the 30 arch and having an apex edge and each section provided with embedded wires whose ends project and are exposed at said apex edge—the projecting wire ends of one section being adapted to be united with those of the other 35 section.

7. An arched chimney-cap comprising two separate sections each forming part of the arch and having an apex edge whereat the two sections join, and means at said apex for 40 joining said sections and holding them together.

In testimony whereof I affix my signature in the presence of two witnesses.

GEORGE F. SMITH.
